(57) **CLAIM**

The ornamental design for a sanitary napkin, as shown and described.

DESCRIPTION

- FIG. 1 is a perspective view of a first embodiment of a sanitary napkin;
FIG. 2 is a front view of the embodiment of a sanitary napkin shown in FIG. 1;
FIG. 3 is a back view of the embodiment of a sanitary napkin shown in FIG. 1;
FIG. 4 is a right side view of the embodiment of a sanitary napkin shown in FIG. 1;
FIG. 5 is a left side view of the embodiment of a sanitary napkin shown in FIG. 1;
FIG. 6 is a top view of the embodiment of a sanitary napkin shown in FIG. 1; and
FIG. 7 is a bottom view of the embodiment of a sanitary napkin shown in FIG. 1.
FIG. 8 is a perspective view of a second embodiment of a sanitary napkin;
FIG. 9 is a front view of the embodiment of a sanitary napkin shown in FIG. 8;
FIG. 10 is a back view of the embodiment of a sanitary napkin shown in FIG. 8;
FIG. 11 is a right side view of the embodiment of a sanitary napkin shown in FIG. 8.

(Continued)

FIG. 12 is a left side view of the embodiment of a sanitary napkin shown in FIG. 8;

FIG. 13 is a top view of the embodiment of a sanitary napkin shown in FIG. 8; and,

FIG. 14 is a bottom view of the embodiment of a sanitary napkin shown in FIG. 8.

Broken lines shown in the figures described above are for illustrative purposes only and form no part of the claimed design.
